DRILLING MACHINE

Anton Van Veen, West Hartford, Conn.

Application November 1, 1935, Serial No. 47,828

2 Claims. (Cl. 77—22)

My invention relates to that class of machine tools wherein a hole or a number of holes may be drilled in an article with the axis of the drill holding spindle or spindles disposed out of line with the axis of the hole or holes being drilled; and a further object of the invention is to provide a machine of this type in which a plurality of holes may be simultaneously drilled in parallel relation in such articles with the spindles or drills relatively diagonally disposed; and a still further object of the invention is to provide a machine in which holes may be simultaneously drilled in articles of smaller sizes.

One form of a machine embodying my invention and in the construction and use of which the objects herein set out, as well as others, may be attained is illustrated in the accompanying drawing in which

Figure 1 is a top view of my improved drilling machine.

Figure 2 is a view in side elevation of the same.

Figure 3 is a view on enlarged scale in longitudinal section on a plane denoted by the dotted line 3—3 of Fig. 1.

Figure 4 is a view in section on a plane denoted by the dotted line 4—4 of Fig. 3.

Figures 5, 6 and 7 are respectively side, sectional and end views of a pinion of a kind suitable for drilling on my improved machine.

Figure 8 is a view partially in section showing the construction of a lantern pinion.

Figure 9 is a detail view, scale enlarged from Fig. 3, illustrating the manner for supporting the work to be drilled.

Figure 10 is a diagrammatic view on reduced scale illustrating a little different arrangement for deflecting the drills into parallel relation.

Figure 11 is a detail view on reduced scale illustrating another modification.

In the accompanying drawing the numeral 6 denotes the spindle carrier or drill head of my improved machine which may be mounted on any suitable base 7 and which may be either slideable on said base or fixed thereon against movement.

This contemplates that either the article to be operated upon or the carrier may either or both be moved relatively to each other. As herein shown a lug 8 projects from the bottom of the carrier and has an actuating rod 9 secured thereto, such rod being connected with any suitable means for imparting reciprocating movement to the carrier 6. Bearing supports 10 extend from the carrier, and spindle supporting blocks 11—12 are secured in the bearing supports and as shown in Fig. 3 of the drawing. These blocks project

into the supports 10 and anti-friction bearings 13 of any suitable type are mounted on the projecting ends of said blocks. A driving pulley 14 is mounted upon said bearings for rotation as by means of a belt or other driving power, said pulley being hollow for frictional or other driving contact with spindle driving members located within the pulley.

A number of spindles 15 are rotatably mounted in the blocks 11—12 in holes 16 which are disposed with their axes out of line with the axes of the active ends of the drills when in operation. These holes may be lined with bushings 17 of any suitable anti-friction material. A number of spindles are employed in each machine, six being shown herein, and they are all of the same general construction so that the description herein will be applied to a single spindle, it being understood that such description will apply equally to all.

A driver 18, preferably of frusto-conical shape in one arrangement and as shown in Fig. 3, is splined to the spindle in contact with the inner surface of the pulley 14 on one side and with a backing roller 19 of the same shape on its opposite side, said roller being rotatably mounted in the blocks 11—12 as by means of stub shafts 20 projecting into said blocks and seated against anti-friction bearings located in line with the axis of said stub shafts. One of these bearings 15 is yieldingly engaged with the end of the stub shaft as by means of a spring pressed plunger 22 and as shown in Fig. 3 of the drawing. An adjusting screw 23 is engaged with the stub shaft at the opposite end of the roller 19 for the purpose of adjusting said roller with respect to the driver 18. A spring 24 is engaged between and with the end of the driver 18 and a collar 25 on the spindle 15 and tends to yieldingly force the driver 18 into contact with the driving pulley 14. An adjusting screw 26 is engaged with an anti-friction bearing 27 seated in the end of the spindle for the purpose of adjusting the position of said spindle; said screw being threaded through a cap 31 that is secured in place in any suitable manner, said cap covering the supporting block 12 and being secured against the flange thereon. The block 12 may be secured in place as by means of screws inserted through a marginal flange thereon, and retaining screws are threaded 50 through said cap to retain the bearings 21 in place.

A chuck 28 of any desired character is secured to the working end of the spindle said chuck receiving a drill 29 which is secured in place in

the chuck in any suitable manner. The drill is slender so that it may readily bend from an inclined position as shown in one instance in Fig. 3 of the drawing into parallel relation with the other drills similarly arranged and forming a part of the machine. The drill is gradually curved from an oblique position in one portion of its length into parallel relation with the drilling ends of the other drills, for this purpose guides 30 of any suitable number, three being shown herein, projecting across a hole in a guide supporting block 31 secured in a guide support 32 projecting from the front end of the carrier 6.

15 This machine is particularly adapted for use in simultaneously drilling a number of parallel holes in devices of diminutive character, as in lantern pinions commonly used in clock mechanism and other mechanisms of the same general type.

20 These pinions each comprises two disks 33 and an arbor 34 and they may be supported in any desired manner, as in a jig of any suitable construction. As herein shown this jig comprises a plate 35 having a drill bushing 36 containing holes spaced and relatively positioned to correspond with the holes to be drilled in the pinions, this bushing being composed of hardened metal and constituting a pattern for the drilling of such holes.

25 30 The jig or holder also comprises a holder plate 38 supported in any suitable manner in front of the bushing 36, said holder plate having a socket 39 containing a spring pressed plunger 40. This plunger has a recess in its end and a recess is also formed in the bushing 36. This provides a very ready means for placing the pinions in position to be drilled, the arbor 34 being normally pressed against the plunger 40 which is thereby pressed inwardly to enable the opposite end of the 35 spindle to be placed in the recess in the bushing 36, the pinions being also readily removed by grasping them and therewith pressing the plunger inwardly enabling the ends of the arbor to be disengaged from the sockets in the bushing and plunger.

40 45 In that form of the structure shown in Fig. 10 the spindles 41 are arranged in parallel relation, having the drivers 42 of cylindrical shape supported by a backing roller 43 of the same shape and the hole in the pulley 44 being of cylindrical shape to fit the drivers. Otherwise the structure is substantially the same as that shown in Fig. 3. Guides 45 are constructed and supported in the same manner as in the device shown in Fig. 3 except that the holes in the guides are relatively formed to cause the drills to be de-

flected from parallel positions where they project from the spindles again into relatively converging shapes and then into parallel relation closer together as will be readily seen.

In this structure the drills 29 are secured to drill extensions 46 which may be used in any of the different forms, said extensions taking the curved form. In Fig. 11 the drivers 47 are secured directly to the drill extensions, or they may be secured directly to the drills.

Wherever the term "drill member" is used herein it will be understood that it covers and includes the drill as a single piece secured within the spindle, or a drill extension, as shown in Fig. 10, or a structure in which the drill or an extension thereof may have the drivers secured thereto as in Fig. 11.

I claim:

1. A drilling machine including a supporting head, a plurality of spindles rotatably mounted with their axes in relatively inclined positions in said head, drivers loosely attached to said spindles, collars secured to said spindles, a pulley encircling said spindles and having an opening with an inclined wall to fit said drivers, a backing roller of frusto-conical shape rotatably mounted in engagement with said drivers, springs located between said drivers and the collars on said spindles to thrust the drivers into contact with said pulley, an adjusting screw in the end of each spindle to adjust its lengthwise position, flexible drill holders secured to said spindles and adapted to receive straight drills of ordinary construction, and means for positioning the working parts of said drills in substantially parallel relation.

2. A drilling machine including a supporting head, a plurality of spindles rotatably mounted with their axes in relatively inclined positions in said head, drivers secured to said spindles, a pulley encircling said spindles and having an opening with an inclined wall to fit said drivers, a backing roller of frusto-conical shape rotatably mounted in engagement with said drivers, stub shafts projecting from the ends of said backing roller, anti-friction bearings for the ends of said stub shafts in axial alignment in said shafts, a spring pressed plunger thrusting against one of said anti-friction bearings, means for adjusting said drivers in an axial direction, flexible drill holders secured to said spindles and adapted to receive straight drills of ordinary construction, and means for positioning the working parts of said drills in substantially parallel relation.

ANTON VAN VEEN. 55
